UNITED STATES PATENT OFFICE

EDWARDS F. SCHERMERHORN, OF BROOKLYN, NEW YORK, ASSIGNOR TO THE RAIL JOINT COMPANY, OF NEW YORK, N. Y., A CORPORATION OF NEW YORK.

INSULATED RAIL-JOINT.

1,207,084.

Specification of Letters Patent. Patented Dec. 5, 1916.

Application filed June 30, 1916. Serial No. 106,861.

To all whom it may concern:

Be it known that I, EDWARDS F. SCHERMERHORN, a citizen of the United States, residing at Brooklyn, in the county of Kings 5 and State of New York, have invented certain new and useful Improvements in Insulated Rail-Joints, of which the following is a specification.

This invention relates to rail joints, and 10 more particularly to joints of the insulated type, and has special reference to a novel and practical improvement in the means for clamping or holding the insulation in place.

Primarily the invention contemplates 15 equalizing the pressure on the insulation clamped between the upper side of the head of the angle bar and the underside of the rail head, and also between the foot flange of the bar and base flange of the rail, thus more 20 evenly distributing the wear on the insulation at these points, and materially increasing the life and efficiency thereof.

More particularly the present invention has in view a novel formation of the bearing 25 faces of the joint bar allowing more uniform compression of the insulation, especially of the insulation arranged at the under side of the rail head to minimize or prevent the cutting of the same.

30 In practice, especially on modern high rails having a large fishing space, there is a distinct tendency, when splice bars are not carefully applied, for the splice bar to enter the fishing of the rails in an inclined or 35 canted position, this tendency being due to the much greater bearing surface for the foot of the splice bar on the rail than for the head thereof. This allows the head of the bar to enter more freely than the foot, 40 with the result that if the splice bar is not carefully applied, it is canted in at the top and out at the bottom, and the tightening of the joint bolts merely aggravates this condition. In consequence of such a condition in 45 an insulated rail joint, the head of the joint bar will have only a slight bearing on the rail head insulation adjacent to the outer edge of the rail head, and the loads imposed on the latter will be concentrated on a comparatively small surface of the insulation, resulting in the rapid destruction thereof 50

along the small bearing surface, whereas if the loads were transmitted uniformly to the entire bearing surface of the insulation underlying the rail head, the compression and 55 wear would be distributed over a greater area, and consequently would have a less destructive effect.

Accordingly, a novel and distinctive feature of the present invention is to form the 60 insulation bearing portions of the joint bar at such an angle that the bar will uniformly compress the insulation plates when the track bolts are tightened, so that no single point thereof is subjected to a greater degree of 65 compression than another, thereby preventing rapid disintegration and destruction of the insulation, and conserving the life of the joint.

With the above and other objects in view, 70 which will more readily appear as the nature of the invention is better understood, the same consists in the novel construction, combination and arrangement of parts herein-after more fully described, illustrated and 75 claimed.

A preferred and practical embodiment of the invention is shown in the accompanying drawings, and although for the purpose of illustration, an angle bar type of joint bar is 80 shown, it will, of course, be understood that the invention may, without departing from the spirit or scope thereof, be applied with equal facility to other types of joint bars used in insulated joints. 85

Accordingly, as illustrated in the drawings Figure 1 is a bi-sected cross sectional view of a rail showing the upper and lower sections of insulation in position, and a joint bar of the ordinary type as it is sometimes 90 applied in a canted position, whereby the head and base sections of insulation are compressed unevenly along lines of contact hereafter more fully referred to. Fig. 2 is a bi-sected, cross-sectional view of a rail showing the upper and lower sections of insulation in position, and a joint bar embodying the features of the present invention prior to its being drawn into final position by the track bolts. Fig. 3 is a view similar to Fig. 100 1, but showing the proper relative positions of the insulation bearing surfaces of the

joint bar when the track bolts are tightened. Fig. 4 is a bi-sected cross-sectional view illustrating a modification of the invention for accomplishing the same results as shown 5 in Figs. 2 and 3, the bar being in a canted position before the tightening of the joint bolts. Fig. 5 is a view similar to Fig. 4, but showing the relative position of the insulation bearing surfaces to the joint bar when 10 the joint bolts are tightened.

Similar reference characters designate corresponding parts throughout the several figures of the drawings.

In carrying the present invention into effect, no changes are contemplated in the general organization of the parts of the rail joint to which the invention may be applied, nor is it proposed to make any radical departure from the structural characteristics 20 of such joints, as the present improvement is susceptible of application to any type of rail joint bar having insulation bearing surfaces. Accordingly, for the purposes of illustration, there is shown in the accompanying drawings, a portion of a rail section R fitted with the upper and lower insulation plates 1 and 2, respectively located beneath the head of the rail and over the base flange thereof.

30 Although the insulation plates 1 and 2 are usually of highly compressed fiber, which is very hard and tough in character, the same is relatively soft as compared with the rails and joint bars, so that under the extreme compression produced by the wheel 35 loads imposed on rails under traffic, the insulation becomes more or less compressed at all points where it is clamped between a face of the joint bar and a portion of the rail. Ordinarily, joint bars for insulated joints have their bearing faces formed on lines which are substantially parallel with the opposing faces of the rails. However, it has been found in applying joint bars having 45 these conventional features, that owing to the form of construction of modern rails and splice bars, and the lack of care with which the latter are frequently applied, the splice bar tends to enter between the upper and lower inclined bearing faces of the rail in a canted position, that is, with the head of the bar inclining inwardly from the perpendicular, and the foot of the bar inclined outwardly to the same degree. This 55 disturbs the desired parallel relation between the bearing surface of the rail and the splice bar as shown in somewhat exaggerated form in Fig. 1, and produces a localized and concentrated imposition of the 60 loads on the insulation at the points P and S, which results in excessive compression of the insulation at these points and consequent rapid destruction. This condition is aggravated and the wear increased at the point P

between the under side of the rail head and 65 the upper face of the bar, by the deflection of the rail head at its upper edges under load, thus producing a "pinching" action on the insulation at P, which results in cutting through the insulation at this point 70 before the remainder of the insulation has been subjected to very much compression or wear. Accordingly, to remedy these conditions, and place the insulation under uniform compression at all points, it is proposed, by the present invention to form the head 3 of the bar 4 (Fig. 2) in such a manner that the bearing face 6 at the top thereof is arranged at a different angle from the opposing bearing face 7 of the rail head. 80 This angle must be formed in such a way as to have an outwardly divergent relation to the bearing face at the under side of the rail head prior to the tightening of the track bolts, as shown in Fig. 2. Stating this 85 feature of the invention another way, the face 6, at the head of the joint bar, lies in a plane designated by the line A—B which is disposed at a lesser angle to the vertical axis X—Y of the bar than the angle of the 90 inclined underside 7 of the rail head with the vertical axis of the rail. By this particular construction, the splice bar is provided with a head whose bearing face is disposed at a non-uniform distance from the 95 adjacent bearing face of the underside of the rail head, the maximum distance between said bearing faces of the splice bar and rail head being adjacent to the outer side of the latter before the joint bolts are tightened, as 100 clearly indicated in Fig. 2.

When the track bolts are tightened, it will, of course, be apparent that the entire joint bar 4 is drawn inwardly toward the web of the rail, and it will be readily seen that if the joint bar has a tendency to assume a canted position such as illustrated in the bar in Fig. 1, the head of the bar will also assume a canted position, but owing to the angle of the face 6, the insulation will 110 be evenly compressed. However, the provision of clearance at the outer edge of the bar, by beveling the head as shown, has the beneficial effect of causing the upper bearing face 6 to assume its proper relation to the insulation and the under side of the rail head, thus securing the desired uniformity of bearing contact. On the other hand, if the joint bar should be applied in a perfectly perpendicular position, its head will 115 contact with the insulation, first at 3°, and if the bar is tightened in this position, the result will be an initial concentration of compression on the insulation at 3°, but as the joint bar is further tightened and loads imposed thereon, the bearing and compression will be distributed along the entire bearing surface at the head of the joint bar, thus,

relieving the insulation from excessive compression at the point of usual greatest wear as at 3^b, and allowing it to resist with its full thickness, the compression produced by the outer side of the rail head under load. Accordingly, when the joint bolts are tightened, as shown in Fig. 3, it will be apparent that the bearing face 6 at the upper side of the joint bar will evenly compress the insulation at all points between the faces 6 and 7, and not more so at the outer edge of the rail head than elsewhere.

Referring to Figs. 4 and 5, which show a modification of the invention, it will be observed that here is shown a construction in which the joint bar 4 has the usual inclined bearing face 8 at the upper side of the head thereof, and the inclination and general direction of this face is parallel to the underside of the rail head, while the under side 10 of the foot 9 of the bar is arranged at a greater angle to the vertical axis of the bar than the upper side of the rail base has to the perpendicular axis of the rail. The general inclination of the bearing face 10 of the under side of the foot of the bar is indicated by the line C—D, and this face lies in a plane which is more nearly at right angles to the vertical axis X—Y of the joint bar and the vertical axis of the rail, than the upper face 11 of the base flange of the rail. That is to say, the feature of providing a joint bar with an inclined bearing face, which is arranged at a greater angle to the perpendicular axis of the bar, than the corresponding bearing face of the rail has to the vertical axis of the rail, may be carried out, as shown in Figs. 2 and 3, or as shown in Figs. 4 and 5, to evenly compress the insulation at all points between the foot of the bar and the base flange of the rail, and to secure uniformly distributed bearing on the insulation at both the top and bottom of the joint bar, if the latter should be applied in a canted position.

With the construction shown in Figs. 4 and 5, it will be apparent that if the bar is originally applied in a canted position, that is, so that the head thereof is inclined farther toward the rail web than the base thereof, the same will draw into a substantially vertical position upon the tightening of the joint bolts, and thereby cause the usual bearing face 8 at the head of the bar to evenly compress the insulation at the underside of the rail head. This is due to the clearance afforded by beveling the underside 10 to the foot flange of the bar. If this bar should be applied in a substantially vertical position originally, that is, so that the bearing face 10 evenly contacts with the insulation section 2 covering the surface 11, the web of the bar may assume a slight out-

wardly inclined relation to the rail web, whereby, upon the tightening of the joint bolts, the head of the bar will draw in and evenly compress the head section of insulation. Thus, the same results will be accomplished as by the beveling of the upper side of the head of the bar, as shown in Figs. 2 and 3. In other words, the construction shown in Figs. 4 and 5 is the reverse of the construction shown in Fig. 3, whereby upon a tightening of the joint bolts, both the head and base sections of insulation are placed under even compression by the bearing faces of the joint bar.

Without further description, it is thought that the many features and advantages of the present invention will be readily apparent, and it will, of course, be understood that various changes in the form, proportion, and minor details of construction may be resorted to without departing from the spirit of the invention or scope of the appended claims.

I claim:

1. A rail joint including a rail having a bearing face disposed at an angle, and a splice bar having a bearing face disposed at a lesser angle to the vertical axis of the bar than said bearing face of the rail is disposed to the vertical axis of the latter.

2. A rail joint including a rail having a head, the underside of which is disposed at an angle, and a splice bar having a top bearing face disposed at a lesser angle to the vertical axis of the bar than the angle of the underside of the rail head to the vertical axis of the rail.

3. An insulated rail joint including a rail having an inclined face, an insulation plate fitting said face, and a splice bar having an inclined bearing face outwardly diverging from said inclined face of the rail prior to the tightening of the bolts.

4. An insulated rail joint including a rail, having an inclined face, an insulation plate fitting said face, and a splice bar having a flat inclined bearing face outwardly diverging from said inclined face of the rail prior to the tightening of the bolts.

5. An insulated rail joint including a rail, an insulation plate, and a splice bar having a head whose bearing face is disposed at non-uniform distance from the adjacent bearing face of the underside of the rail head, the maximum distance between said bearing faces of the splice bar head and rail head being adjacent the outer side of the latter prior to the tightening of the bolts.

6. An insulated rail joint including a rail, an insulation plate, a splice bar having a head provided with a top bearing face outwardly diverging from the inclined face at the underside of the rail head, the maximum distance between said bearing faces of

the splice bar head and rail head being adjacent the outer side of the latter prior to the tightening of the bolts.

7. An insulated rail joint including a rail, an insulation plate, a splice bar having a head provided with a flat top bearing face outwardly diverging from the inclined face at the underside of the rail head, the maximum distance between said bearing faces of

the splice bar head and rail head being adjacent the outer side of the latter prior to the tightening of the bolts.

In testimony whereof I hereunto affix my signature in the presence of two witnesses.
